UNITED STATES PATENT OFFICE.

LOTHAR VON GRAVE, OF WALLINGFORD, CONNECTICUT, ASSIGNOR TO THE
H. L. JUDD & COMPANY, OF NEW YORK, N. Y.

DESIGN FOR A PICTURE-FRAME.

SPECIFICATION forming part of Design No. 23,216, dated April 24, 1894.

Application filed March 27, 1894. Serial No. 505,344. Term of patent 3½ years.

To all whom it may concern:

Be it known that I, LOTHAR VON GRAVE, a subject of the King of Prussia, residing at Wallingford, Connecticut, have invented and 5 produced a new and original Design for Picture-Frames, of which the following is a specification, reference being had to the accompanying drawing, wherein the figure shows a face view of a frame illustrating my design, 10 one-half only of said view being shown in full lines, the other half being shown in outline.

The essential features of my design consist in a central rectangular portion surrounded by an openwork leaf-like portion having chasing 15 thereon and following the general contour of the central rectangular portion.

In the drawing *a* represents a central ornamental rectangular portion, provided with an opening *b*. Surrounding this portion *b* is an openwork leaf-like portion *c* having chasing *d* thereon and following the general contour 20 of the central portion *a*, except at the top of the frame, where there is a leaf-like extension *e* projecting therefrom.

What I claim is—

25 The design for a picture frame substantially as shown and described.

LOTHAR VON GRAVE.
